JOHAN GUNNAR HOLMSTRÖM, OF STOCKHOLM, SWEDEN

RADIOTELEGRAPH SYSTEM

Application filed January 13, 1931, Serial No. 508,396, and in Sweden January 14, 1930.

The object of the present invention is a 5 telegraph system affording possibilities for all telegraph offices within the same country or within any other large area to intercommunicate in a direct way for the transmission of messages by means of modern start-and-stop teletype or facsimile telegraph apparatus.

Under present conditions the offices have 10 to find their way along the telegraph lines, and as these afford facilities for only a restricted number of connections, the messages have to be sent through so-called collecting offices for retransmission to their destination. 15 The lines are not only expensive but permit only of a restricted number of possibilities of transmission and thus impose considerable delays upon the messages.

The present invention has adopted the use 20 of radio communication for the connections between the several intercommunicating offices. Each office is equipped with an oscillatory receiving circuit exactly tuned to a certain individual wave-length and with a 25 great number of sending circuits, which are either permanently tuned or capable of being tuned in a simple way to the wave-lengths of each of the other offices belonging to the same communication system. In other words, each 30 office is provided either with as many circuits as there are corresponding offices or with a restricted number of circuits capable of being adjusted, by the change of their electric constants, to any of the circuits of the corresponding offices.

Besides the necessary start-stop facsimile or other kind of telegraph apparatus such as a Morkrum or other known teletype apparatus, each station must therefore be provided 40 with a switching device including a contact contrivance for each of the oscillatory circuits of the other offices within the same communication area, these latter contrivances being capable of being connected by means 45 of the switching device, to the transmitter and the receiver of the sending office. In this way the telegraph apparatus is connected to the circuit emitting electro-magnetic waves of a frequency corresponding to that of the 50 office with which communication is required.

It being necessary, on account of the great number of participating offices, to dispose of a great number of waves, it is essential that the characteristic frequency sent out by each office should be carefully tuned, be kept constant and be exempt from strange frequencies produced by attenuation or other disturbing causes.

To attain this end it is proposed to utilize 55 oscillatory circuits of very small attenuation controlled in any known manner such as by the piezo-electric principle or by means of tuning forks.

In view of the large number of wave- 60 lengths required it will be advisable to choose the waves within frequency bands that have not yet been officially appropriated to any defined purposes. With the aid of controlled oscillatory circuits having a constant frequency 65 it will be possible to reduce the separation between two adjacent frequencies to a very small amount and to occupy only a comparatively small frequency band for a large number of offices or stations.

In order to increase the number of offices 70 or stations working within the same frequency band it will also be possible to have recourse to heterodyne reception, by appropriately modifying the circuits in well known manner, the different receiving stations all working on approximately the same primary wave, and the station required being determined by the deflection of the sending wave from the primary wave. The station is then 75 selected by means of a secondary wave high or low frequency determined by the difference 80 between the wave-lengths of the sending and the receiving offices. As mentioned above the possibility of working many stations within a small frequency band greatly depends upon 85 the constancy of the individual frequencies used by the different stations. For this reason controlled oscillatory circuits are, under present conditions best adapted to the purpose.

It is also evident that the use of any contrivance intended to improve the constancy such as thermostats and others may 90 also be desirable.

In order to illustrate the invention a description is given below of the operating pro- 100

cedure applied in a telegraph system working on the lines in view. Reference is made in this description to the attached diagram.

The stations may be imagined to be designated by the letters A, B, C, D, E etc., N being the station shown on the diagram, while the other stations are practically duplicates thereof but are not shown. This latter station, as well as all the other stations, is preferably provided with a start-stop teletype apparatus, such as the Morkrum type, whose main construction forms no part of the invention, but whose impulse transmitter is designated by 1 as a key and the receiver thereof by 2. 3 represents the aerial of the station, if any such structure is used. The aerial is supposed to include a grounded induction coil 4. To this latter coil are inductively coupled two coils, 5 and 6, and a feed back coil or tickler coil 40. Coil 5 forms part of the particular oscillatory circuit 7 of illustrated station N, which includes A condenser 8 and coil 5. By means of a switching device consisting, for instance of a double conductor cord 9 and a plug 10, coil 6 can be connected to any of the jacks 11_A, 11_B, 11_C—11_K, 11_L, 11_M, 11_O etc. arranged in a switchboard and corresponding to the respective other communicating stations (not shown). Each jack 11 is connected to its particular oscillatory circuit 12_A, 12_B, 12_C—12_K, 12_L, 12_M, 12_O, and each of these circuits is tuned, by the adjustment of inductance 13_A, etc., and capacity 14_A, etc., so as to correspond, together with coil 6, to each of the other imagined stations A, B, C—K, L, M, O etc. By the insertion of plug 10, for instance into jack 11_K corresponding to station K the oscillatory circuit 14_K, 13_K and 6 is connected to the aerial 3.

The insertion of the plug further results in the connection of the high tension points 30, 31, over the rest contacts 15 and 16 of relay 17, to the valve receiver 41. If station K is engaged this is revealed by the action of receiving device 2 upon the telegraph apparatus. If no such action is visible station K is free and the telegraph apparatus of illustrated station N can be started. For this purpose, contact 19 of the sender 1 is brought into direct contact with operating contact 18, in accordance with the requirements of the telegraph system used. For instance, when contact 19 touches contact 18, the circuit of a local battery 20 is closed over relays 17 and 21. Relay 17 then connects the high tension points 30, 31 of the circuit corresponding to station K to valve transmitter 22 producing the radiation from aerial 3 of waves corresponding to the characteristic frequency of station K. Relay 21 is slow-working and therefore keeps contact 23 closed as long as the transmission lasts. Each time contact 19 is moved to rest contact 24 the current circuit is closed through relay 25, thus effecting the connection of valve transmitter 22 to the

particular oscillatory circuit 7 of the station over contacts 26 and 27. This will result in the emission of the wave of illustrated station N during the interval when contact 19 is in contact with rest contact 24. If desired, circuit 7 can also be kept in continuous operation while transmission is going on from the station N on another wave. This will serve to indicate to other stations that station N is engaged.

When another station, E for example of the series (not shown), wants to send a message to illustrated station N its plug 10 is inserted into its jack 11_N of its switching device, which starts the motor of its telegraph apparatus and depresses the key several times of the keyboard of station E. Electromagnetic waves of the frequency particular to present station N are then sent out and will work upon the circuit 7 of this station N. The valve receiver 41 of this station N is connected over rest contacts 28, 29 of relay 25, and the electromagnet 2 of the receiver will therefore start the teletype apparatus or the like (not shown) and will work upon its selecting and printing mechanism causing the letter E to be printed. This is the preferable calling procedure.

Station N replies to the call by inserting its plug 10 in the E jack 11_E of the calling station and by pressing down for instance the key of its start-stop apparatus, of the station E thus indicating that the signal has been perceived and that the transmission may begin. When a key is pressed down at station N, the receiver 41 with the receiving relay 2 is cut out, by the action of relay 17, from the oscillatory circuit E of station N, while the transmitter 22 is switched in and produces in this circuit oscillations of such intensity that the circuit acts as a transmitter and gives signals to station E of the nature determined by the transmitting mechanism of the telegraph apparatus. This is possible because at station E the receiver 41 and the receiving relay 2 are connected to the oscillatory circuit 7 corresponding to the wavelength of station E, when no key is depressed.

When the illustrated station N is to send a message to another station, K for instance, the cord plug 10 is inserted in jack 11_K of the switchboard group of jacks shown. In this way the transmitter 22 and the receiver 41 are connected to an oscillatory circuit tuned to the wavelength which is special to the station K. The sending operator at station N now starts the motor of the start-stop apparatus (not shown), either by pressing down a key (also not indicated on the diagram), by throwing over a switch or by some similar primary circuit closing arrangement, and then operates the key such as 1 of the keyboard several times. By this means oscillations are also produced in circuit 12_K, to which the apparatus has just been connected.

If the distant station K is free, it is apprised of the call through the fact that the motor of its apparatus is started and the letter N is printed on the apparatus. At station K its 5 plug 10 is then inserted in its jack 11_N and, by tapping on its key, announces its readiness to receive. When the sending operator of present station N receives the sign K on her apparatus, she knows that she may begin 10 transmission. She then sends her message in the usual way and gets the receipt from distant station K, whereupon cord plug 10 at this station N is removed from jack 11_K. The receiving relays 2 of stations N and K 15 being thus no longer subject to any impulses, a time-delay relay such as 21 breaks the circuits of the respective motors and makes them stop.

If at the moment when station N connects 20 its apparatus to the oscillatory circuit special to distant station K, the latter station is engaged in correspondence with some other station, this correspondence must not be disturbed by station N sending out 25 oscillations characteristic to said station K. Station N must therefore be made aware of the fact that station K is engaged. This can be arranged for in many ways and with notice taken of the fact that station K may be 30 engaged either in receiving on its own wavelength or in sending on any other wave. One solution of this problem consists in the transmitting oscillatory circuit 12_K of station N being used as a receiving circuit and made to 35 work, in case impulses are received from the station K, upon the motor of the present station N, starting it, before the start key or switch of the same has been operated. The sending operator of this station N will then 40 have to wait some time after inserting plug 10 in jack 11_K, say 15 or 30 seconds, before starting her motor. If it has not been started after this time by impulses from the other distant station, she knows that station 45 K is free and that she may start the motor and begin transmission from the oscillatory circuit 12_K of present station N.

If station K is engaged in receiving waves 50 of the frequency characteristic to station K, the oscillatory circuit 12_K of station N as soon as it has been connected to the N aerial of the station, receives the waves emitted and works on the receiving relay 2 of station N.

If said station K is engaged in sending 55 on another wavelength than its own, special indicatory oscillations must be sent out from it during the whole time transmission is in progress. The present invention is equipped for this eventuality by making the oscillatory 60 circuit 7 of imaginary station K emit oscillations of the wavelength of this station, either continuously as long as transmission from said station K takes place on another wavelength, or merely in the intervals between the signals transmitted but during the

whole time transmission is going on from said station K in the manner described above in respect to present station N. The latter alternative is presumably preferable, as it avoids simultaneous transmission from two 70 circuits.

Evidently the contact devices of the switching equipment as well as the leads to the equipment must be constructed so as to avoid influences upon the high frequency oscillatory circuits caused by changes of capacity resulting from the switchboard operations. For this reason it is desirable that any action 75 exercised upon or originating from the oscillatory circuits should take place through intermediary relays and that the currents working upon, or closed or modified by, these relays should be either continuous or of low frequency.

The present invention can be used not only 80 for start-stop but also for facsimile telegraphs the same not being shown as forming no actual part of the invention. In the case of facsimile telegraphy a motor has also to be started in the transmitting as well as 85 the receiving apparatus before transmission can begin. The switching devices and the engagement signals described above are therefore applicable also to facsimile telegraphs. 90

Having now particularly described the 95 nature of my invention and the manner of its operation, what I claim is:—

1. Apparatus for intercommunication between a group of stations by means of radiant energy, including at each station, a plurality of oscillatory circuits having different frequencies individually corresponding with the reception frequencies of all the stations in the group including that of the sending station, and means at each station including a switching device providing for the simultaneous use at said station of two of said oscillatory circuits for transmission purposes, one for radiating the wave for traffic having a 100 frequency corresponding with the reception frequency of one of the other stations in the group, and of the other of said two circuits for indicating that the sending station is busy 105 and having the same frequency as the reception frequency of said sending station. 110

2. Apparatus for intercommunication between a group of stations by means of radiant energy, including at each station, a plurality of oscillatory circuits having different frequencies individually corresponding with the reception frequencies of all the stations in the group including that of the sending station, and means at each station including a switching device providing for the simultaneous use at said station of two of said oscillatory circuits for transmission purposes, one for radiating the wave for traffic having a frequency corresponding with the 120 reception frequency of one of the other stations in the group including that of the sending station, and of the other of said two circuits for indicating that the sending station is busy 125 and having the same frequency as the reception frequency of said sending station. 130

- tions in the group, and connected to reception devices in the sending station which is automatically operable to receive incoming waves during idleness of the switching device
- 5 and cessation of transmission from the station, and of the other of said two circuits for indicating that the sending station is busy and having the same frequency as the reception frequency of said sending station.
- 10 3. Apparatus for intercommunication between a group of stations by means of radiant energy, including at each station, a plurality of oscillatory circuits having different frequencies individually corresponding with
- 15 the reception frequencies of all the stations in the group including that of the sending station, reception devices associated at each station with one of said oscillatory circuits, and means at each station including a switching device providing simultaneously for dissociation of said reception devices from said one oscillatory circuit and for the use at said station of two of said oscillatory circuits for transmission purposes, one for radiating the
- 20 wave for traffic having a frequency corresponding with the reception frequency of one of the other stations in the group, and of the other of said two circuits for indicating that the sending station is busy and having
- 25 the same frequency as the reception frequency of said sending station.
4. Apparatus for intercommunication between a group of stations by means of radiant energy, including at each station, a plurality of oscillatory circuits having different frequencies individually corresponding with the reception frequencies of all the stations in the group including that of the sending station, the oscillatory circuit at each
- 30 station which corresponds in reception frequency to that of the wave transmitted thereby being self-oscillating during transmission of messages upon said wave in order to distinguish one station from the other in the
- 35 group by means of the dissimilarity of the beat oscillations whereby to provide for a large number of frequencies and corresponding stations within a relatively limited frequency band, and means at each station including a switching device providing for the simultaneous use at said station of two of said oscillatory circuits for transmission purposes, one for radiating the wave for traffic having a frequency corresponding with the
- 40 reception frequency of one of the other stations in the group, and of the other of said two circuits for indicating that the sending station is busy and having the same frequency as the reception frequency of said sending
- 45 station.
